Specification for Design.

Patented Feb. 17, 1920.

Application filed August 19, 1919. Serial No. 318,608. Term of patent 7 years.

To all whom it may concern:

Be it known that I, BRUCE BAIRNSFATHER, a subject of the King of Great Britain and Ireland, residing at The Spa House, Bishopton, Stratford-upon-Avon, England, captain in the Army, have invented a new, original, and ornamental Design for a Motor-Car Mascot or Ornament, of which the following is a specification, reference being had to the accompanying drawings, forming part thereof, in which—

Fig. 2 is a side elevation of the same.

I claim:—

The ornamental design for a motor car mascot or ornament, as shown.

Dated this 18th day of July 1919.

BRUCE BAIRNSFATHER.
